JP Office Action dated Feb. 23, 2011 for JP Appln. No. 2010-25686.

Primary Examiner — John Windmuller

(74) *Attorney, Agent, or Firm* — Bose Corporation

CLAIM

The ornamental design for a remote control, substantially as shown and described.

DESCRIPTION

FIG. 1 is a perspective view of a remote control as seen from the front, top and right side;

FIG. 2 is a top view thereof;

FIG. 3 is a bottom view thereof;

FIG. 4 is a right side view thereof, the left side view is a mirror image of the right side view;

FIG. 5 is a rear view thereof; and,

FIG. 6 is a front view thereof.

The broken lines shown in the Figures are for illustrative purposes only and form no part of the claimed design.
